UNITED STATES PATENT OFFICE.

FRED REESSING, OF MOLINE, ILLINOIS.

NUT-LOCK.

SPECIFICATION forming part of Letters Patent No. 556,642, dated March 17, 1896.

Application filed May 31, 1895. Serial No. 551,134. (No model.)

To all whom it may concern:

Be it known that I, FRED REESSING, a citizen of the United States, and a resident of Moline, in the county of Rock Island and 5 State of Illinois, have invented certain new and useful Improvements in Nut-Locks; and I do hereby declare that the following is a full, clear, and exact description of the invention, which will enable others skilled in the art to 10 which it appertains to make and use the same, reference being had to the accompanying drawings, which form a part of this specification.

My invention relates to improvements in 15 nut-locks adapted more especially for use in connection with railroad-rails and for connecting parts of machinery which are subjected to vibration whereby the nuts are liable to work loose.

20 The object of the invention is to provide an improved nut-lock which shall be simple and economical in construction, and which shall possess superior advantages with respect to efficiency in operation.

25 The invention consists in the novel construction and combination of parts hereinafter fully described and claimed.

In the accompanying drawings, Figure 1 is 30 a side elevation showing my improved device used for locking the nuts of the bolts which connect two railroad-rails together. Fig. 2 is a detail perspective view showing the locking-arm thrown out of engagement with the nut. Fig. 3 is a cross-section on the line $x-x$, 35 Fig. 1. Fig. 4 is a plan view of the locking-arm detached. Fig. 5 is a sectional view of a modification.

In the said drawings the reference-numeral 1 designates two railroad-rails, and 3 a fish-40 plate, which may be of any ordinary or suitable construction. These rails and fish-plates are formed with aligned apertures, through which pass bolts 4 provided with nuts 5, which may be square, hexagonal or of any other 45 form desirable.

Connected with the fish-plate at one side of each of the bolts 4 is a screw-bolt 6, which engages with a correspondingly-threaded aperture in the fish-plate. This bolt is formed with 50 an angular head 7, having an aperture with which engages a headed pivot-pin 8. Pivoted

to this pin between the head thereof and one of the sides of the bolt is a locking-arm 9 having a flattened head 10.

The numeral 11 designates a screw-pin, also 55 engaging with a corresponding recess in the head 7, to which is pivoted a plate 12, which, when the locking-arm is thrown into engagement with the nut, can be turned over the end thereof and thus hold it in place. 60

In the modification shown in Fig. 5 the bolt is made with a bottom left-hand screw-threaded recess and the screw-bolt is formed with corresponding screw-threads. The locking-arm 9^a in this instance is bent backward 65 at a right angle and the extremity turned inward at an angle, so that when turned on its pivot said extremity will engage with the side of the nut and lock the same. The plate 12^b is also bent at an angle at its free end and its 70 axis is at a right angle to the axis of plate 9^a, so that it can be turned sidewise with respect to said latter plate, and its turned or inwardly-bent end engaging with the outer edge of plate 9^a will prevent the same from turning 75 on its pivot, thus locking the nut.

While I have shown and described the device as being used for connecting two railroad-rails together, it is obvious that it may be employed for all other purposes for which 80 nut-locks are applicable.

Having thus fully described my invention, what I claim is—

In a nut-lock, the combination with the screw-bolt adapted to be passed through apertures in a railroad-rail and fish-plates and having a screw-threaded recess in one end and a head at the other end, the nut fitting on said bolt, the headed screw-bolt fitting in said recess, the locking-plate pivoted to one 90 side of the head and the plate pivoted to the end of the head adapted to be turned down against the side of said locking-plate and hold it in place, substantially as described.

In testimony that I claim the foregoing as 95 my own I have hereunto affixed my signature in presence of two witnesses.

FRED REESSING.
